(57) **CLAIM**

I claim the ornamental design for a closure, as shown and described.

DESCRIPTION

FIG. 1 is a right side perspective view of a closure embodying my design;

FIG. 2 is a left side perspective view of the closure as shown in FIG. 1;

FIG. 3 is a front elevational view of the closure as shown in FIG. 1;

FIG. 4 is a top plan view of the closure as shown in FIG. 1; and,

FIG. 5 is the left rear perspective view of the closure shown in FIG. 1.
